UNITED STATES PATENT OFFICE.

PETER K. DEDERICK, OF LOUDONVILLE, NEW YORK.

BALING-PRESS.

SPECIFICATION forming part of Letters Patent No. 280,456, dated July 3, 1883.

Application filed May 15, 1883. (No model.)

To all whom it may concern:

Be it known that I, PETER K. DEDERICK, of Loudonville, county of Albany, and State of New York, have invented certain Improvements in Baling-Presses, of which the following is a specification.

My invention relates to that class of presses for which Letters Patent were granted to me October 29, 1872, No. 132,566 and No. 132,639, 10 and the various modifications of the same for which Letters Patent have since been granted to me, particularly May 2, 1882, No. 257,153, and to Letters Patent granted Huntington and Carter, May 7, 1872, No. 126,394, and in this 15 instance consists in the method of applying the power and of improvements in the partitions for passing the bands.

Figures 1 and 4 are perspective views illustrating my improvements. Figs. 2, 3, 5, 6, 20 and 7 are sectional views.

Similar letters represent similar parts.

It should be observed that in Letters Patent No. 126,394 and No. 257,153, above referred to, the power is applied by means of a horse-lever 25 direct to the double-acting toggle, whereas in this instance the power is communicated to the machine by gearing and rope or chain.

A, Fig. 1, represents the frame of the press, which may be constructed in any suitable manner; or as shown.

B represents the pitman or one arm of the toggle, which is attached to a reciprocating traverser, which plays in the frame A. C represents the other arm of the toggle, of which I 35 preferably use two, one above and the other below the arm B, to which they are pivoted at D.

E is a shaft, which is secured to the frame of the press above and below and passes through 40 the arms C, and also through the cross-head or cam F, which is located on the shaft E between them. The power is applied to this cam-head by means of suitable gearing or by a worm, as shown in Figs. 4 and 5; or the cam-head F is 45 used as a drum and reciprocated by means of ropes or chains, as shown in Figs. 1 and 2, thus forcing the toggle B C over its center from right to left and from left to right, as more fully explained in Letters Patent No. 257,153, 50 above referred to. The power might be applied to a separate head or drum located at

the top or any other part of the shaft E, provided it and the cam-head F were both secured rigidly to the shaft E. The form of the cam-head F may be varied from a true segment of 55 a circle when ropes, chains, or other than gear attachments are employed, as shown in Fig. 7.

In Letters Patent No. 152,084, June 16, 1874, and No. 177,219, May 9, 1876, I have shown how my press may be geared to be driven by 60 a separate motor; but in both cases the crank or toggle makes a continuous revolution instead of a reverse movement, and thus double-acting the toggle, as is done in this. I 65 secure this reverse movement in the case of gearing by two heavy balance-wheels or pulleys, G G, Fig. 5, moving in opposite directions and loosely mounted on the shaft, so as to be moved toward the clutch-head H and engage with it either by friction or other clutch. 70 The clutch-head H is secured rigidly to the shaft, and the balance-wheels or weighted pulleys, being loose on the shaft, can alternately 75 engage and disengage with it, and, moving in opposite directions, a reverse movement is thus produced, while the power is stored or secured by the momentum of the balance-wheels or pulleys. The clutch-head may be secured by a feather in the shaft, and moved, if preferred, and with the same effect. When 80 the power is communicated by ropes or chains, as shown in Figs. 1 and 2, a single weighted pulley, I, will answer, and if may also be used as a belt or drive-pulley and mounted on the shaft between drums or spools J for winding 85 the ropes, the one rope winding at the top and the other at the bottom of the spool, so that when either drum or drive-pulley is moved to bring the friction or other clutch in contact with the drums alternately the ropes will 90 alternately wind and unwind and vibrate the cam-head F, to which the rope K is attached, and thus vibrate the toggle B C from side to side, or double-acting it. The power might be increased by mounting the weighted drive-pulley 95 and clutches on a separate shaft geared to the drum or spool-shaft; or a steam or hydraulic cylinder and piston-rod might be used and the rope or chains attached to it direct, as shown in Figs. 3 and 7, or be geared to the 100 piston-rod by means of a rack, as shown in Fig. 5, L being the steam-cylinder, and M the pis-

ton rod or shaft, so that, as the piston is moved back and forth by means of the direct action of the steam, the power of the press is vibrated as in preceding cases, and thus by its action 5 condenses the hay in sections into bales.

Fig. 6 represents the partition or follower through which the bands or wires are passed in order to bind the bales, and differs from those shown in former patents referred to, in that one or more slots on each side are diagonal across its face, as shown at N, Fig. 6, for the purpose of binding the bales by a continuous wire, as more fully set forth in Letters Patent granted me on this method of binding bales 15 April 10, 1883, No. 275,366.

Having thus fully described my invention,

what I claim, and desire to secure by Letters Patent, is—

1. In a baling-press, the combination of the double-acting toggle B C with the cross or cam head F, reversed or vibrated back and forth by means of gearing, ropes, or chains, substantially in the manner and for the purpose set forth.

2. In combination with the baling-case, the partition provided with diagonal slots, for the purpose set forth.

PETER K. DEDERICK.
